UNITED STATES PATENT OFFICE.

MEDORA AUSTIN FRITZ, OF OAKLAND, CALIFORNIA.

STAMP AND ADVERTISING BOOK.

1,292,750.

Specification of Letters Patent.

Patented Jan. 28, 1919.

Continuation of application filed July 19, 1915, Serial No. 40,551. This application filed February 15, 1918. Serial No. 217,465.

To all whom it may concern:

Be it known that I, MEDORA AUSTIN FRITZ, a citizen of the United States, residing at Oakland, in the county of Alameda and State of California, have invented certain new and useful Improvements in Stamp and Advertising Books, of which the following is a specification, reference being had to the accompanying drawing.

10 This invention relates to an improved advertising device and more particularly to a form of book having a sealed envelop pocket bound in with the leaves of the book in which are placed stamps, the value of which 15 exceeds the cost at which the book is sold. By this means the book will find a ready sale, the advertisements carried on the various pages thereof being sufficient to pay for the extra cost of the stamps plus a profit to 20 the makers of the same.

The principal object of my invention is to provide a booklet of this character which is neat in appearance and in which the stamps are securely bound and are held in a 25 moisture proof compartment before they are used and while being used are readily accessible.

The manner in which these objects are accomplished will be set forth in the following specification and more specifically 30 pointed out in the appended claims.

In the accompanying drawings:—

Figure 1 is a view in perspective of my improved book showing the same partly 35 opened and a portion of the envelop pocket broken away to disclose the position of the stamps therein.

Fig. 2 is an enlarged sectional view on the line 2—2, Fig. 1.

40 Fig. 3 is a view showing the shape of the blank in which the envelop pocket is formed.

Referring to corresponding parts by the same numerals of reference. 1 denotes the cover leaves of the book, and 3 denotes the 45 leaves which may carry memorandum, advertising, or information of any desired description, which will add to the desirability or attractiveness of the book. 4 denotes in general my sealed envelop pocket, this 50 pocket being formed from a single sheet of material preferably the semi-transparent waxed or paraffin paper. This pocket is formed of the rectangular back

portion 5 having the front portion 6 of the same shape and size, which is folded 55 over the back portion and fastened by adhesive along the opposite edge 7. Two side flaps 8 and 9 are provided, these flaps including the points 11 being somewhat wider than half the width of the pages of 60 the book and are folded over the rectangular portion along the lines 10. The front and back portions are about the size of two leaves of the book and in assembling the 65 pocket thus formed is bound between the pages 3 and the back of the book, the whole being held by staples 14 or some equivalent fastening means, the points 11 of the flaps 8 and 9 projecting through the back of the 70 leaves. The stamps are placed between the portions 5 and 6 of the envelop pocket before binding and thus when the book is completed they are held between two portions of the waxed paper and the open edges of 75 the pocket are closed by the flaps 8 and 9.

The book thus constructed is sold for less than the cost of the stamps in the pockets so as to induce the ready sale and to provide a medium for carrying advertisements, which is not quickly thrown away. The 80 buyer of this device cuts the side flaps along the edges 10, pulls the flaps out of the binding and throws them away. The rectangular portion thus left is then cut at the edges 13, thus forming two leaves between which 85 the stamps are held at the back. One side may be cut at a time and when the stamps on that side are used the other side may be cut in like manner. Even while the stamps are being used they are preserved from 90 sticking against other objects due to the fact that they are held between the surfaces of the portions 5 and 6 which as heretofore explained, are made of paraffined or waxed 95 paper.

While I have shown and described the preferred embodiment of my invention it will be understood that minor changes may be made in detail and design without departing from the spirit thereof.

This application is a continuation of my application Serial No. 40,551, filed July 19, 1915.

What I claim as new and wish to cover by Letters Patent is:—

1. A book of the character described com-

prising, a cover, a plurality of leaves, a closed envelop bound between said cover and said leaves.

2. A book of the character described comprising a cover, a plurality of leaves, a substantially rectangular envelop bound along its center between said cover and said leaves.

3. A book of the character described com-

prising a cover, a plurality of leaves, an envelop bound between said cover and said leaves, said envelop having flaps, the points of which are bound in with said leaves forming a sealed envelop pocket at the front and back of said book.

MEDORA AUSTIN FRITZ.
